UNITED STATES PATENT OFFICE.

WILLIAM R. FEARN, OF SAVANNAH, GEORGIA, ASSIGNOR TO HIMSELF AND
WESLEY C. VINCENT, OF SAME PLACE.

RAILROAD-SWITCH.

SPECIFICATION forming part of Letters Patent No. 235,421, dated December 14, 1880.

Application filed March 10, 1880. (Model.)

To all whom it may concern:

Be it known that I, WILLIAM R. FEARN, of Savannah, in the county of Chatham and State of Georgia, have invented a new and useful

5 Improvement in Railroad-Switches, of which the following is a specification.

The object of my invention is to provide for opening and closing the switches of a railroad-track from a train passing over them, so as to 10 place control of the switches in the hands of the engineer or train-men; and my invention consists, first, in a switch wherein the switch-levers are connected to a rod extending in both 15 directions from the switch, and the said rod is fitted with crank-levers that extend between the tracks, as hereinafter described; second, in a swinging block or key hinged to the lower end of a hanger that depends from the car or locomotive platform, and fitted for being swung 20 up and down by a lever and rod, whereby the block may be turned down to move the crank-levers of the switch, and the switch shifted from one track to another, as required.

The construction and operation will be more 25 particularly described hereinafter with reference to the accompanying drawings, wherein—

Figure 1 is a plan view of the track and switch. Fig. 2 is a longitudinal section of the same, showing also the switch-moving device 30 as fitted to a car. Fig. 3 is a cross-section on line $x-x$ of Fig. 1. Fig. 4 is a cross-section on line $y-y$. Fig. 5 is a similar view on line $z-z$, and Fig. 6 is a vertical section of the switch-key and its hanger.

35 Similar letters of reference indicate corresponding parts.

Referring to Fig. 1, $a-a$ are the rails of the main track, $b-b$ the rails of siding, and $c-c$ the moving switch-rails. The switch-rails c are 40 pivoted at one end, and at their moving ends are secured upon a block or plate, d , that is fitted to slide transversely of the track. e is a signal connected with block d in such manner that it will exhibit the position of the 45 switch-rails.

f is a rod fitted at one side of the track upon a block, f' , and extending in both directions therefrom the required distance.

50 $g-g$ are toggle-levers connected one with the rod h and the other with the block d , that carries the switch-rails.

g' is a pin or projection upon the block f' , with which pin the toggles g come in contact when moved by rod f .

h is a lever hung on the cross-tie next to 55 block d , and having its outer end connected to bar f through one of the toggles g , while its inner-end carries a pin, h' , (see Figs. 1, 2, and 3.) that extends into a recess in the block d when the switch is closed to either track, and 60 is withdrawn therefrom by the movement of rod f to shift the switch by means of the connections described.

As the rod f is moved in the direction of arrow 1 the section of toggle attached thereto 65 moves across from stud g' to the cross-tie without pushing the slide-block d , and during this lost motion the lever h withdraws the pin h' , when the toggle, pushing the unlocked slide-block, causes the switch-rails $c-c$ to connect the 70 tracks $a-b$, when the lever h is again moved to lock the slide-block d . In moving the rails $c-c$ to connect the two parts of track a , the bar f is moved in the direction of arrow 2, when the 75 toggle-section attached thereto is moved across from the cross-tie to the stud g' without actuating the slide, so that during the lost motion the pin h' may be withdrawn; then, working against the stud g' , the toggle-section moves the slide and brings the switch-rails $c-c$ between 80 the two parts of track $a-a$.

$i-i'$ are crank-levers fitted in suitable bearings on the cross-ties of the main track $a-a$, and having their outer ends pivoted to rod f , while their inner ends are bent upward between the 85 rails a . These levers $i-i'$ are fitted one above and the other below the level of rod f , and their crank ends are bent in opposite directions, so that the movement of i in the direction of the arrow shall move the switch to the siding, and 90 the movement of i' in the same direction shall move the switch to the main track. In the main track, at the opposite side of the switch, is a lever, i'' , similarly arranged and connected to rod f , so that its movement by a car approaching the switch shall open the switch to 95 the main track.

l is a crank-lever connected to rod f , and extending to and bent up between side-track rails b , so that its movement in the direction of the 100 arrow by a train approaching the switch shall shift the switch to the siding.

- p* is a crank-lever fitted for operation by a train passing from the main track to the siding, and intended to allow the train to set the switch to the main line after passing.
- 5 The means for moving the crank-levers of the switch are shown in Figs. 2 and 6, and are as follows: *i'* is the platform of an engine or car. *k* is a hanger attached rigidly to under side of the platform, and stiffened by braces *k'*. *l* is a block or key hung upon the lower end of hanger *k* by a knuckle-joint, so that it may swing transversely of the car. *m* is a crank-lever hung in a slot of hanger *k*, having its lower end connected by a link with key *l*, and its upper end connected with a treadle, *n*, that extends up through the platform *i'* to a convenient position for operation by the train-men. *o* is a spring bearing on treadle *n*, and tending to throw the treadle up and the key *l* down.
- 10 *p* is a plate or lug on platform *i'*, engaging with notches in treadle *n*, to retain the same down against the action of spring *o*. These parts are arranged in such position that when the key is turned down by pressure on treadle *n* it will come in contact with the switch-levers as the train moves forward, and when turned up at one side by rise of the treadle the key and hanger will pass above the switch-levers without contact.
- 15 The operation is as follows: A train approaching the switch is carried to the main track or siding, (or the switch closed in case it is open,) without stopping the train, by turning down the key *l* to come in contact with the bent end of the particular switch-lever that
- 20 operates the switch, as desired.
- 25
- 30
- 35

The signal *e* shows at all times the condition of the switch, so that the engineer of the train may see what movement is required, if any, to carry the train in the desired direction.

40 It will be understood that the crank-levers are arranged, in practice, a suitable distance apart and from the switch for the proper operation of the mechanism before the train reaches the switch.

45 Having thus described my invention, I claim as new and desire to secure by Letters Patent—

1. The combination, with the rod *f*, operating as described, and the switch-rail slide-block *d*, 50 of their connecting-toggle *g*, working between a fixed stud, *g'*, and a cross-tie to give lost motion, as and for the purpose specified.

2. In switches, the combination, with the sliding block *d*, carrying the switch-rails, and the rod *f*, by which the block *d* is moved, of the lever *h*, connected with rod *f* and carrying the locking-pin *h'*, substantially as and for the purposes set forth.

3. The hanger *k*, hinged block or key *l*, lever *m*, and treadle *n*, combined with the car and engine platform, substantially as and for the purposes set forth.

4. In combination with the notched treadle *n*, that operates the key *l*, the spring *o* and plate *p*, as and for the purposes set forth.

WM. ROBERT FEARN.
